UNITED STATES PATENT OFFICE.

FREDERICK GIRTANNER, OF NEW YORK, N. Y., ASSIGNOR TO WILLIAM DE L. WALBRIDGE AND EDWARD J. BERWIND, TRUSTEES, OF SAME PLACE.

DOWNDRAFT BOILER-FURNACE.

SPECIFICATION forming part of Letters Patent No. 629,350, dated July 25, 1899.

Application filed January 13, 1899. Serial No. 702,021. (No model.)

To all whom it may concern:

Be it known that I, FREDERICK GIRTANNER, a citizen of the United States of America, residing at New York, Manhattan borough, county of New York, and State of New York, have invented certain new and useful Improvements in Downdraft Boiler-Furnaces, of which the following is a specification.

My invention has reference to improvements in steam-boiler furnaces, and particularly to downdraft furnaces—that is to say, those in which the air necessary for the combustion of the fuel or the maintenance of the fire is conducted to the fuel from above and the products of combustion are carried away from below.

The object of my present invention is to produce a more thorough combustion and a higher heat than has been obtainable with the furnaces hitherto proposed. These results I accomplish by a peculiar distribution or arrangement of the air-supply orifices or tubes relative to the furnace and to the charging-openings thereof.

My invention consists, therefore, in the combination, with the supporting-grate for the fuel, of a series of air-supply tubes or orifices arranged at the top of the furnace and contiguous with the front and side walls of the same and a series of air tubes or orifices arranged intermediate of the tubes at the side walls and preferably adjacent to the charging-openings.

My invention also embodies other novel features of construction used in connection with those just set forth, as fully pointed out in the following specification and claims and illustrated in the annexed drawings, in which—

Figure 1 represents a front elevation of a boiler and furnace embodying my invention, part of the same being broken away. Fig. 2 is a side elevation of the same. Fig. 3 is a sectional plan. Fig. 4 is a vertical section on the line 4 4, Fig. 6. Fig. 5 is a sectional plan with the covers of the air-orifices and the coal-openings removed. Fig. 6 is a vertical section on the line 6 6, Fig. 4. Fig. 7 is a section on the line 7 7, Fig. 4. Fig. 8 is a vertical section of a modified form.

Similar letters and numerals of reference designate corresponding parts throughout the several views of the drawings.

Referring to the drawings, the letter A designates the furnace, which is built substantially rectangular in cross-section, with front and rear walls 1 and 2 and with side walls 3, said furnace being located substantially in front of the head of the boiler B. The grate 4 may be of any construction commonly used in boiler-furnaces; but preferably a rocking grate provided with mechanism 5 for actuating the several grate-bars is employed. The air necessary for effecting the combustion of fuel (generally bituminous coal) is introduced into the furnace from above through tubes a, which are so arranged as to effect the distribution of the air-supply in jets at the most favorable points for producing a uniform and complete combustion and to prevent clinkering at the walls of the furnace, and also to prevent caking in the mass of the fuel. To insure a proper downward feed of the fuel while being consumed, the rear wall is outwardly and downwardly inclined.

Referring now particularly to Figs. 5, 6, and 7 of the drawings, the letters b designate the charging-openings for fuel, which are arranged at the top of the furnace and in the longitudinal direction of the same—that is, transversely to the boiler—and are preferably placed equidistant apart. The air-tubes a are arranged contiguous to the front and side walls of the furnace A and on three sides of the charging-openings. These tubes may open directly to the atmosphere; but in practice I prefer to conduct the air necessary for combustion through a suitable flue or flues 6, located exterior to the front wall 1 of the furnace and communicating at their upper ends with a horizontal chamber or chambers 7 located at the top of the furnace and communicating with all the tubes a. The air in passing through the flues 6 and the chambers 7 is warmed. The products of combustion pass from near the bottom of the furnace through a passage or passages 8 into the usual combustion-chamber 9, and in the present example, where I have shown a return tubu-

lar boiler, the gases after passing through the boiler-tubes are conducted upwardly to the chimney through the uptake 10 and suitable flues. (Not shown.) The quantity of air supplied to the tubes *a* is regulated by means of suitable gates 11, located at the air-inlets 12 to the flues 6. The fuel is introduced into the furnace through the charging-openings *b*, previously described, and the chimney draft induces currents of air to pass through the openings 12, flues 6, and chambers 7 and from the latter through the tubes *a*, which said tubes form streams or jets of air directed against the fuel contiguous with the front wall, with the side walls, and at points intermediate of all the walls. The action of each jet is to supply air against a particular point of the fuel, and in view thereof the combustion of fuel gradually rises vertically along the paths of the downward jets of air, with the result that vertical holes or openings are formed in the fuel along the lines of air-supply. The coal adjacent to such openings naturally moves laterally, and consequently the body of the fuel is being continually broken up or agitated and caking or packing is positively prevented. The tubes located adjacent to the sides of the charging-openings and which I have designated by the reference-letters *a'* serve to break up the fuel between the end walls of the furnace. The number of such tubes can be increased or decreased by increasing or decreasing the number of the charging-openings. The charging-openings *b* are closed by suitable doors *c*, which are preferably hinged, and the portions of the chambers 7 above the tubes *a* and *a'* are closed by removable plates *d*, so that air can be fed directly to the tubes from above without passing through the flues 6. The plates *d*, laterally adjacent to the charging-openings *b*, may be provided with side flanges *e* to form a hopper or guide for the fuel when it is delivered to said charging-openings. Near the lower end of the furnace and at the front of the same is formed a series of openings *f*, closed by doors *g*, which said openings are intended, essentially, for cleaning out the furnace. The doors *g* may be provided with openings, closed by adjustable draft-slides *h*, for the purpose of admitting air through the openings *f*, if desired. The ash-pit door *i* is so fitted as to close the ash-pit *j* substantially against the ingress of air; but air may be admitted through the ash-pit door if circumstances so require. An air-distributer *l*, Figs. 6 and 7—such, for instance, as a perforated clay or iron tube—is preferably arranged at the rear of the furnace-wall 2 and above the passages 8, through which the products of combustion enter the combustion-chamber, so as to introduce air in a divided condition into the flame emanating from said passages. The supply of air to the distributer may be regulated or entirely

shut off by a usual form of draftslide or slides located at one or both ends of the distributer.

While I have shown my improvements embodied in a furnace adapted for return tubular boilers, it is of course evident that the same furnace, with slight modifications, is adapted for use with other forms of boilers—such, for instance, as water-tube boilers of various types, upright boilers, marine boilers, and the ordinary fire-flue boilers. It is also evident that the charging-openings may be located at the front of the furnace instead of at the top of the same.

In place of the grate 4 as a fuel-support a hearth 4* may be used, as shown in Fig. 8, said hearth being closed against ingress of air into the furnace from below. The ashes may be raked from the hearth through the doors or openings *f*.

What I claim as new is—

1. In a downdraft boiler-furnace, the combination of a support for fuel, a series of air-supply tubes arranged at the top of the furnace and contiguous with the front and side walls of the same to direct jets of air downwardly through the fuel, and a series of air-tubes arranged intermediate of the tubes at the side walls for the same purpose, substantially as described. 85

2. In a downdraft boiler-furnace, the combination of a support for fuel, a series of charging-openings for the furnace, a series of air-tubes arranged adjacent to the front and side walls of the furnace to direct jets of air downwardly through the fuel, and a series of air-tubes arranged intermediate of the charging-openings for the same purpose, substantially as described. 95

3. In a downdraft boiler-furnace, the combination of a support for fuel, a series of charging-openings located at the top of the furnace, a series of air-tubes arranged at the top of the furnace adjacent to the front and side walls of the same to direct jets of air downwardly through the fuel, and a series of air-tubes arranged adjacent to the charging-openings for the same purpose, substantially as described. 105

4. In a downdraft boiler-furnace, the combination of a support for fuel, a series of charging-openings located at the top of the furnace, a series of air-tubes arranged adjacent to the front and side walls of the furnace, to direct jets of air downwardly through the fuel, a series of air-tubes arranged intermediate of the charging-openings for the same purpose, air flues and chambers arranged adjacent to the walls and top of the furnace, and means for regulating the supply of air to said flues and chambers, substantially as described. 115

5. In a downdraft boiler-furnace, the combination of a support for fuel, a series of air-supply tubes arranged at the top of the furnace adjacent to the front and side walls of 120

125

130

- the same, and said tubes being adapted to direct jets of air downwardly through the fuel, a series of air-tubes arranged intermediate of the air-tubes at the side walls for the same purpose, an air chamber or chambers above the lines of tubes with which chambers said tubes communicate, and removable plates forming part of the inclosure of said air chamber or chambers, substantially as described. 50
- 5 6. In a downdraft boiler-furnace, the combination of a support for fuel, a series of charging-openings located at the top of the furnace, a series of air-tubes arranged adjacent to the front and side walls of the furnace 55 to direct jets of air downwardly through the fuel, a series of air-tubes arranged intermediate of the charging-openings for the same purpose, an air chamber or chambers with which said tubes communicate, and removable plates forming part of the inclosure of said chamber or chambers and provided with upwardly-extending flanges adjacent to the charging-openings, substantially as described. 60
- 10 7. In a downdraft boiler-furnace, the combination of a support for fuel, a series of charging-openings for the furnace, a series of air-tubes arranged adjacent to the front and side walls of the furnace to direct jets of air downwardly through the fuel, a series of air-tubes arranged intermediate of the charging-openings for the same purpose, an opening or openings provided with doors and regulators, and a passage or passages 8 leading through the rear wall of the furnace to the combustion-chamber and located at or near the bottom of the furnace, substantially as described. 70
- 15 8. In a downdraft boiler-furnace, the combination of a support for fuel, a series of air-supply tubes arranged at the top of the furnace and contiguous with the front and side walls of the same to direct jets of air downwardly through the fuel, a series of air-tubes arranged intermediate of the tubes at the side walls for the same purpose, a rear wall 2 for the furnace having a downwardly and outwardly inclined inner wall, and a passage or passages through the rear wall of the furnace communicating with the combustion-chamber and located 75 near the bottom of the furnace, substantially as described. 80
- 20 9. In a downdraft boiler-furnace, the combination of a support for fuel, a series of air-supply tubes arranged at the top of the furnace and contiguous with the front and side walls of the same to direct jets of air downwardly through the fuel, a series of air-tubes arranged intermediate of the tubes at the side walls for the same purpose, and a plurality of contracted passages 8 located near the bottom of the furnace and passing through 85 the rear wall of the same to communicate with the combustion-chamber, substantially as described. 90
- 25 10. In a downdraft boiler-furnace, the combination of a support for fuel, a series of air-tubes arranged at the top of the furnace contiguous with the front and side walls of the same to direct jets of air downwardly through the fuel, a series of air-tubes arranged intermediate of the tubes at the side walls for the same purpose, a rear wall 2 for the furnace having a downwardly and outwardly inclined inner wall, and a passage or passages through the rear wall of the furnace communicating with the combustion-chamber and located 95 near the bottom of the furnace, substantially as described. 100
- 30 11. In a downdraft boiler-furnace, the combination of a hearth closing off the ingress of air to the furnace from below, a series of air-supply tubes arranged at the top of the furnace and contiguous with the front and side walls of the same to direct jets of air downwardly through the fuel, and a series of air-tubes arranged intermediate of the tubes at the side walls for the same purpose, substantially as described. 105
- 35 40 45

In testimony whereof I have hereunto set my hand in the presence of two subscribing witnesses.

FREDERICK GIRTANNER.
